Patented Aug. 12, 1958

183,349

COMBINED HELICOPTER AND GLIDER

Clyde Carl Johnson, Inglewood, Calif.

Application June 5, 1957, Serial No. 46,486

Term of patent 14 years

(Cl. D71—1)

Figure 1 is a rear perspective view of the combined helicopter and glider showing my new design;

Figure 2 is a side elevational view of the combined helicopter and glider;

Figure 3 is a front elevation thereof;

Figure 4 is a top plan view of the combined helicopter and glider;

Figure 5 is a rear elevation thereof; and

Figure 6 is a bottom plan view thereof on a reduced scale.

I claim:

The ornamental design for a combined helicopter and glider, as shown.
